VARIABLE INDUCTANCE DEVICE

Franz Otto, Neu-Finkenkrug, near Berlin, Germany, assignor to Steatit-Magnesia Aktiengesellschaft, Berlin, Germany

Application May 5, 1936, Serial No. 78,004
In Germany July 2, 1935

11 Claims. (Cl. 171—242)

This invention relates to induction apparatus, particularly for high frequency circuits using a compressed iron powder core, and has for its object to provide apparatus of this class, which is 5 of compact design and can be readily installed.

The employment of iron powder cores brought about a considerable economy in space over the formerly used air core coils, but this advantage was partly lost in the known types of self-induction coils using such cores for the reason that the means for the adjustment of the iron powder core were made quite bulky. As it is desirable in most instances to balance the inductance value of the unit by moving a part of the iron powder core, it is necessary to construct the adjusting means as compactly as possible. This is 10 of particular importance in apparatus in the communication art, wherein, as a rule, not only one but several induction coils are employed 15 which must be arranged as free from coupling as possible, i. e., with the axes of the coils disposed vertically to one another.

All these requirements are met by apparatus constructed according to the present invention 20 which consists in providing an insulating member the outline of which is in the form of a cube comprising, besides means for supporting the coil windings and the iron powder core, a means for adjusting a part of the iron powder core. Such 25 an insulating member affords the advantage that at any position of the axis of the coil it can be assembled with other cubic insulating members of the same kind to form units having any desired value of inductance, each of which is individually adjustable.

Figure 1 is an elevational view of an insulating body constructed in accordance with the present invention; Fig. 2 is a section on line 2—2 of Fig. 1; Fig. 3 is a section on line 3—3 of Fig. 1; Fig. 4 is a vertical sectional view of a modified form 30 of the device; Fig. 5 is a section on line 5—5 of Fig. 4; Figs. 6 and 7 illustrate a further modification in vertical section and in plan view, of a body having a core of the spool type; Fig. 8 is 35 another modification of the device; Fig. 9 is a vertical sectional view of a modified form of the device equipped with a simplified arrangement for adjusting the core member; Fig. 10 is a vertical section of another modification of the invention in which the core is divided into three parts; and Figs. 11 and 12 are each sectional views showing other means for adjusting the core.

Referring to the drawings, and particularly to 40 Figs. 1 to 3, an insulating member *a* is provided,

which is equi-dimensional on all sides and hence cubic in form. Chambers *b* for the reception of the coil winding and chambers *c* for the accommodation of the iron powder core are provided in the body *a*. A portion *d* of the core is firmly connected with the insulating member *a* in any suitable manner whilst the other portion *e* of the core is movably disposed in the cubic insulating body *a*. For adjusting the movable portion *e* a screw *f* made of insulating material is provided and is arranged in a semicircular trough of the insulating member *a*. A rib in the semicircular trough engages a groove of the screw *f* to prevent axial displacement thereof during its turning movement. The movable core 5 portion *e* is provided with a pressed or cut thread *g* which cooperates with the screw *f*, so that rotation of the screw *f* causes a longitudinal displacement of the portion *e* and hence changes the characteristics of the magnetic circuit.

The construction shown in Figs. 4 and 5 is similar to the one just described, the only difference relating to the form of the core. Whereas a divided H type core is employed in the construction according to Figs. 1 to 3, the second embodiment uses a shell type core divided in one plane, though the divisions may be made also in different planes. The cubic insulating member *a* is correspondingly adapted to the different form of the core.

In the embodiment shown in Figs. 6 and 7 an iron powder core is employed which has the form of a yarn spool. For adjusting the induction value of the device, the movable end disc *h* of the core is eccentrically guided in the insulating member *a*. By rotating the end disc *h* the circumference thereof is caused to be more or less coaxial with the circumference of the other end disc *i* of the spool shaped iron powder core. The insulating member *a* is again cubic and adapted to the form of the core.

A further embodiment provided with a divided core of the spool type is shown in Fig. 8. The enlarged end of the core portion *i* is movable and the enlarged end disc *h* firmly connected with the cubic insulating body *a*. The cylindrical portion of the core *i* has a pressed or cut thread formed therein which cooperates with a corresponding female thread formed in the insulating member *a*.

In the construction shown in Fig. 9 the adjusting device is produced in a simpler manner. To the shaft of the movable core portion *i* a relatively short threaded bushing *k* of insulating material is secured, which cooperates with a

short female thread in the insulating member a_4 . The threaded bushing k is preferably slotted and rides in the manner of an expanding ring on the shaft of the core portion i_2 so that rotation of the core part i_2 will cause it to ride in and out of the insulating body to change the value of the inductance of the device. The construction further differs from the embodiments according to Figs. 6 to 8 in so far as instead of a stationary 10 end disc a fixed end ring l is used into which the shaft of the fungiform portion i_2 extends. The form of the insulating member a_4 is adapted to that of the core and to the adjusting device.

In the construction according to Fig. 10 the 15 core comprises two portions m and n secured in the insulating member a_5 . Through both core portions m and n a screw threaded core part o of compressed iron powder is inserted, for which a female thread is provided in the portion n . By 20 means of a rib p and a clearance q on the circumference of the end disc the core portion n is specially secured against rotation.

Figs. 11 and 12 show further possibilities for the adjustment of the movable portion of the 25 iron powder core. In the construction according to Fig. 11 sloping faces t are provided on that side of the end discs of the spool shaped core portion i_2 opposite from the stationary separate front face l , and a correspondingly inclined face 30 is formed on the insulating member a_7 . In this way, longitudinal displacement of the core portion is effected when the core is rotated.

As shown in Fig. 2, it is possible to secure in the shaft of the movable core portion i_5 one or 35 more pins u which engage a helical groove v of the insulating member, longitudinal displacement of the core portion i_5 being caused by rotation as in the construction described above.

The insulating member is preferably made 40 from pressed insulating materials poor in electric loss, such as polystyrol.

As set forth above, all of the modifications include a body of insulation constructed to have the outline of a cube and formed with square 45 shouldered end portions having recesses therein for the reception of an adjustable core part. In every instance, the central portion of the body is provided with means to mount an energizing winding. The reactance of each unit may be 50 varied by changing the relative positions of the divided core parts. It will be appreciated that the units combine with each other readily to produce reactors having higher values than that of a single unit. As the outline, or contour, of 55 each unit is cubic, it will seat against a neighboring unit with a minimum of wasted space, and the units may be combined so that the magnetic axis of the core of each unit is normal to that of a neighboring unit. In this way, there 60 is little or no coupling or mutual inductance between the units. If desired, the units may be built up with the axis of the cores in the same line, in which case the coupling between the combined units may be utilized. In any event, the 65 adjusting means for the core may be kept readily accessible regardless of the relative position of each unit to its neighbor.

I claim:—

1. A reactor of the class described, including 70 a body of insulating material having a pair of opposed sides each formed with an outwardly facing recess connected by a bore, said bore being

of smaller cross-sectional area than the cross-sectional area of the recesses in a plane normal to the axis of said bore, and a core received in the bore and having parts disposed in said recesses. 5

2. A reactor of the class described, including a substantially cubical body of insulating material having a pair of opposed sides each formed with an outwardly facing recess and connected by a bore, said bore being of smaller cross-sectional area than the cross-sectional area of the recesses in a plane normal to the axis of said bore, and a core received in the bore and having parts disposed in said recesses. 10

3. A reactor of the class described, including 15 an insulating body of substantially cubical form formed with a pair of opposed outwardly facing recesses connected by an unobstructed bore, said bore being of smaller cross-sectional area than the cross-sectional area of the recesses in a plane 20 normal to the axis of said bore, and a multi-part core received in said bore and having parts disposed in said recesses.

4. A reactor of the class described, including 25 an insulating body formed with a pair of opposed outwardly facing recesses connected by an unobstructed bore, said bore being of smaller cross-sectional area than the cross-sectional area of the recesses in a plane normal to the axis of said bore, and a multi-part core received in said 30 bore and having parts disposed in said recesses.

5. A reactor of the class described, including 35 an insulating body formed with a pair of opposed outwardly facing recesses connected by a bore, said bore being of smaller cross-sectional area 40 than the cross-sectional area of the recesses in a plane normal to the axis of said bore, a multi-part core received in said bore and having parts disposed in said recesses, and means for adjusting the parts of the core with respect to each other.

6. A reactor in accordance with claim 5 in which the core is spool-shaped and divided, and said adjusting means including oppositely formed sloping faces, one of which is formed on said 45 body and the other of which is formed on an end part of said core.

7. A reactor in accordance with claim 5 in which said core is spool-shaped and divided, and said adjusting means including a pin carried by 50 a part of said core and engaging a helical groove formed in said body.

8. A reactor in accordance with claim 5 in which said core is spool-shaped, and said adjusting means consisting of a slotted threaded bushing of insulating material cooperating with a corresponding thread formed in said body. 55

9. A reactor in accordance with claim 5 in which said core is spool-shaped, and said adjusting means consisting of a short threaded 60 bushing of insulating material cooperating with a corresponding thread formed in said body.

10. A reactor in accordance with claim 5 in which said core is spool-shaped, and said adjusting means consisting of a thread formed in said 65 body and a cooperating thread formed on a portion of said core whereby the position of the core in the body may be changed to alter the reactance of the device.

11. A reactor in accordance with claim 5 in 70 which the insulating body is cubical in form.

FRANZ OTTO.
